(57) **CLAIM**

The ornamental design for a blood glucose meter, as shown and described.

DESCRIPTION

FIG. 1 is a front perspective view of a blood glucose meter, showing our design.

FIG. 2 is a bottom rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front elevation view thereof wherein a needle is extended; and,

FIG. 10 is another front elevation view thereof wherein a test strip is inserted.

The broken lines shown in the drawings are included for purpose of illustrating portions of the blood glucose meter that form no part of the claimed design.

1 Claim, 10 Drawing Sheets
